CARRIER FOR SOLID OBJECTS, INCLUDING
BLOCKS OF SALT AND THE LIKE

Robert C. Geisler, 112 Exmoor Ave.,
Glen Ellyn, Ill. 60137

Filed June 7, 1972, Ser. No. 260,705

Term of patent 14 years

Int. Cl. D8—05

U.S. Cl. D8—51

FIG. 1

FIG. 3

FIG. 1 is a front elevational view of a carrier for solid objects, including blocks of salt and the like embodying my new design; the appearance of the opposite side being a mirror image thereof.

FIG. 2 is a top plan view thereof.

FIG. 3 is a front perspective view thereof.

I claim:

The ornamental design for a carrier for solid objects, including blocks of salt and the like, as shown and described.
